VACUUM TUBE

Walter van Braam Roberts, Princeton, N. J., assignor to Radio Corporation of America, a corporation of Delaware

Application September 28, 1928
Serial No. 308,976

4 Claims. (Cl. 250—27.5)

This invention relates to vacuum tubes and more particularly to a vacuum tube having a cathode energized by an alternating current.

Usually, when an alternating current is utilized to heat the filament comprising the cathode of an electron discharge device or vacuum tube, due to the difference of alternating potential across the filament terminals an objectionable hum manifests itself in the loud speaker of a radio receiver when one or more vacuum tubes of the character described are utilized therein.

The object of this invention is to provide an electron discharge device having a cathode energized by an alternating current which shall not have this hum characteristic. This is done by providing a filament which, although it is energized by an alternating current presents an equi-potential surface.

By providing a filamentary cathode closed upon itself and by causing an alternating heating current to flow therein by induction, I obtain a cathode which presents a substantially equi-potential surface, and which, when utilized in a radio receiver does not cause humming.

The accompanying drawing illustrates ways in which the invention may be carried out and utilized in practice.

Figs. 1 and 2 of the drawing being diagrammatically and partly in section, plan and elevation views respectively, of a cathode and heating and supporting means therefor built according to my invention;

Fig. 3 shows a manner in which auxiliary electrodes may be placed about the cathode, and

Fig. 4 shows a rectifier structure utilizing the features of the invention.

Referring to Figs. 1 and 2 the numeral 1 indicates an electron emitting filamentary cathode of the direct or indirect heater or coated type closed upon itself and surrounded preferably by an evacuated toroid 3 concentric therewith. The toroid or ring shaped container 3 is preferably made of glass. Cathode 1 acts as a short-circuited secondary of a transformer, the other elements of which comprise an iron core 5 which may be made of laminated strips of iron, and a primary coil 7 to which is fed an alternating current. The alternating current fed to the coil 7 may be stepped up or down if desired by another transformer (not shown), the latter transformer being supplied from any available source of alternating current as, for example, a house lighting supply.

Spacers 9 may be provided for supporting filament 1. They may consist of circular discs of a

metal or of an insulating material such as mica having suitable holes 11 formed therein for supporting the filament. If made of metal, as they may be, they will tend to act as shields between different electrode systems grouped about the 60 cathode, and also by their heat dissipating action they will reduce emission from the cathode at points between different electrode systems. A common lead 13 should also be provided for all external circuits to be used in connection with 65 cathode 1.

Fig. 3 indicates a manner in which various electrodes may be grouped about a cathode built according to this invention. This figure shows the cathode and electrode structure removed from 70 the heating apparatus. Numerals 15, 17, 19 and 21 indicate anodes, and numerals 15', 17', 19' and 21' indicate the respective leads thereto. Numerals 23, 25, 27 and 29 indicate leads leading to control electrode structures or grids mounted 75 within anodes 15, 17, 19 and 21 respectively. The anodes may be supported within an evacuated envelope 3 by any suitable means such as spacers 45 built along lines similar to spacers 9 except that they should have holes provided therein sufficiently large to accommodate the anodes. The control electrodes may be similarly supported by spacers (not shown) within the anodes.

The three electrode systems comprising, for example, anode 15, the control electrode 23 and the 85 portion of cathode 1 within anode 15, may be utilized either for rectification, production of oscillations or for amplification of radio frequency or audio frequency currents, or any combination thereof. If desired one of the three electrode 90 systems may be utilized as a detector in combination with the other three electrode systems. While I have illustrated a structure in which the filament cooperates with four grid plate structures, it is to be understood, of course, that any 95 number of electrode systems for any purposes desired may be placed about filamentary cathode 1. A single lead-in 13 is shown in Fig. 3 for making contact with the cathode but a greater number may be provided if desired.

As only filament 1 completely links with the magnetic circuit set up by the primary 7 of the transformer, currents will only be set up in the cathode 1, and no currents of any harmful value will be set up in the other electrodes of the device. Further, since cathode 1 is electrically closed upon itself and heavy currents of low potential are therefor generated therein by induction, between any two points thereof there cannot exist a substantial difference in potential 110

such as to cause an objectionable hum when the tube is utilized in a radio receiver and hence this cathode presents a substantially equi-potential surface. Also, since the heating current flowing in the cathode is produced by induction, no appreciable current need flow in the cathode lead wire 13, which fact avoids the difficulty of sealing wires carrying large current through the glass envelope.

10 Fig. 4 diagrammatically shows an arrangement of anodes about a cathode built according to the invention for use as a full wave rectifier. Numerals 40 indicate anodes, 41' the leads thereto, 42 the cathode and 42' the lead thereto. The 15 cathode energizing system (not shown) is similar to that illustrated in Figs. 1 and 2.

Although there has been shown forms in which my invention may be carried out and utilized it to be understood that the scope of my invention is 20 not to be limited thereby except as indicated in the appended claims.

I claim as my invention:-

1. An electron discharge device comprising a toroidal shaped evacuated envelope, a ring shaped 25 cathode concentrically arranged therein, a plurality of partitions within and dividing the envelope into a plurality of independent chambers, said partitions also acting to support the cathode at intermediate points thereof, grid and anode electrodes supported within each of the chambers and concentrically arranged about that portion of the cathode housed within the chamber, and means for heating the cathode by magnetic induction.

30 2. An electron discharge device comprising an evacuated envelope, a closed conductive circuit constituting a cathode mounted within the envelope, a magnetic circuit interlinked with said cathode and substantially symmetrically disposed 35 with respect thereto, a plurality of partitions

within and dividing the envelope into a plurality of independent chambers, said partitions also acting to support the cathode at intermediate points thereof, and grid and anode electrodes supported within each of the chambers and concentrically arranged about that portion of the cathode housed 80 within the chamber.

3. An electron discharge device comprising a cathode and a plurality of cooperating electrodes arranged in groups along said cathode, said cathode consisting of a closed metallic circuit 85 substantially symmetrically disposed about an interlinking magnetic circuit which is also linked by a primary winding adapted to be connected to a source of alternating voltage, 90 whereby said cathode is heated by induction without the development of substantial differences of potential between any of its parts at any instant, and metallic shielding means interposed between said groups of cooperating electrodes to prevent the transfer of energy therebetween, said cooperating electrodes and shielding means being 95 so disposed as to avoid the completion of any metallic path linking said magnetic circuit other than said cathode.

4. An electron discharge device comprising an evacuated envelope, a closed conductive circuit constituting a cathode mounted within the envelope and substantially symmetrically disposed about an interlinking magnetic circuit which is 105 also linked by a primary winding adapted to be connected to a source of alternating voltage, whereby said cathode is heated by induction without the development of substantial differences of potential between any of its parts at any instant, 110 a plurality of groups of cooperating grid and plate electrodes disposed along different sections of the cathode, and metallic shields interposed between adjacent electrode groups.
